UNITED STATES PATENT OFFICE.

CHARLES KUNZE, OF NEWARK, NEW JERSEY, ASSIGNOR TO P. WIEDERER
& BROTHER, OF NEW YORK, N. Y.

DESIGN FOR A MIRROR OR BRUSH BACK.

SPECIFICATION forming part of Design No. 19,049, dated April 16, 1889.

Application filed February 26, 1889. Serial No. 301,261. Term of patent 3½ years.

To all whom it may concern:

Be it known that I, CHARLES KUNZE, a citizen of the United States, residing at Newark, in the county of Essex and State of New Jersey, have invented a new Design for Backs for Mirrors or Brushes; and I do declare the following to be a full, clear, and exact description of the invention, such as will enable others skilled in the art to which it applies to make and use the same, reference being had to the accompanying drawing, and to the letters and figures of reference marked thereon, which form a part of this specification.

15 The drawing shows a face view of my new design for the surface ornamentation of the backs of mirrors or brushes.

20 The essential feature of my new design consists in a diagonal band between two groups of raised fan-like leaf ornaments emanating from two volutes at the top and bottom of the back.

25 A is a mirror or brush back. B are two groups of raised fan-like leaves emanating from two volutes, C C, at the top and bottom of the back. D is a depressed band between the groups B of leaves.

E is a raised ornament on said band D.

F is the handle, the lower end of which is bent or curved laterally.

30 G are embossed leaves on said handle. H is a band surrounding the leaves.

J are leaves above the band H and at the bottom of the back A, and K is a stippled body or background.

35 Having thus described my invention, I claim as new and desire to secure by Letters Patent—

The design herein shown and described for the surface ornamentation of mirror or brush backs, consisting of two groups of 40 raised leaves emanating from volutes at the top and bottom of the back, a depressed diagonal band between said groups of leaves, and a raised ornament on said band, substantially as set forth.

45 In testimony whereof I affix my signature in presence of two witnesses.

CHARLES KUNZE.
